UNITED STATES PATENT OFFICE.

CHARLES E. SEEMAN AND LOUIS V. BARACH, OF PITTSBURGH, PENNSYLVANIA.

SECTIONAL BILLIARD CUE.

Application filed June 16, 1922. Serial No. 568,710.

To all whom it may concern:

Be it known that we, CHARLES E. SEEMAN and LOUIS V. BARACH, citizens of the United States, residing at Pittsburgh, in the county of Allegheny and State of Pennsylvania, have invented certain new and useful Improvements in Sectional Billiard Cues, of which the following is a specification.

10 This invention relates to certain new and useful improvements in cues used to impel the balls in billiard and other games.

Important objects of the invention are to provide a cue which is capable of being readily separated into sections and which is provided with a hollow butt portion forming a chamber in which the shaft portion of the cue may be conveniently housed, thereby providing compactness to facilitate the handling, packing and transportation of the cue.

Another object of the invention is to provide a sectional cue, of the type stated, in a manner as hereinafter set forth which includes replaceable section connecting elements capable of maintaining the cue rigid and unyielding when assembled regardless of the frequency that said sections are separated and assembled. In sectional cues now commonly in use the utility of the cue is completely destroyed when the section connecting elements become worn from use, because preventing a positive rigid connection eminently essential for the proper use of a cue.

Further objects of the invention are to provide a cue of the character specified which includes buffer means for mitigating the annoyance caused by the prevalent habit of 40 players of thumping the butt end of the cue upon the floor and further to protect the cue butt from injury due to such thumping action, which is simple in its construction and arrangement, strong, durable and efficient in its use, attractive in appearance and comparatively inexpensive to manufacture.

With these and other objects in view, that will appear in the following description, our present invention is a cue that embodies the peculiar features of construction and novel arrangement of parts hereinafter explained in detail, specifically pointed out in the appended claims, and 50 illustrated in the accompanying drawing, which forms a portion of this specifica-

tion and wherein like numerals of reference designate corresponding parts throughout the several views, and in which:—

Figure 1 is a longitudinal sectional view 60 of a cue in accordance with our invention.

Figure 2 is a like view of a modified form.

Referring in detail to the drawing Figure 1 illustrates a cue comprising a butt section 1 and a shaft section 2, which in 65 combination form a straight tapering cue of the usual regulation contour.

The butt section 1 consists of a hollow body member 3, forming a chamber 4, and is preferably constructed from light metal, 70 namely, aluminum or the like. The upper end of the chamber 4 is open, while the lower end thereof is formed with a bottom 5 of considerable thickness.

The body member 3 is enclosed in a casing 6, which is preferably made from bakelite or any other suitable composition material and molded around the body member 3; or the case 6 may be constructed in the form of a tube of suitable material and 80 slipped over the body member 3.

The upper end 7 of the body member 3 projects above the upper end of the casing 6 and is threadably engaged, as at 8, by the buffer casing 9. The lower end 85 10 of the body member 3 extends below the lower end of the casing 6 and is threadably engaged, as at 11, by a ferrule 12. The outer diameters of the buffer casing 9 and the ferrule 12 are such as to form an 90 unbroken, symmetrical continuity, relatively to the periphery of the casing 6.

The buffer 13, constructed from rubber and semi-spherical in contour, is detachably fixed in the buffer casing 9 by the turned 95 in upper edges 14 of the latter, and its engagement with the ring 15. The ring 15 is formed with peripheral threads in engagement with the threaded inner wall of the buffer casing 13. A set screw 13', extending through the wall of the buffer casing 13 and engaging the body member 3, is employed to lock the buffer elements 100 against accidental release upon the body member 3.

The shaft section 2 comprises a hollow body member 16, enclosed in a casing 17. The member 16 and casing 17 are made from materials corresponding to those employed in the construction of the butt section 1 above described.

The lower end of the body member 16

is provided with a tip 18 of the usual construction and the upper end 19, thereof projects above the upper end of the casing 17 and is threadably engaged as at 20, 5 by a ferrule 21. The periphery of the ferrule 21 is in tapering alinement with the peripheral surfaces of the ferrule 12 and the upper end of the casing 17, contiguous thereto.

10 The faces of the abutting ends 10 and 19 of the body members 3 and 16, respectively, are each provided with an embedded sleeve 22 having outer threads to provide threaded engagement, as at 23, with respective ends 10 and 19.

The sleeves 22 are mounted in respective parts in accurate vertical alinement, relatively to each other, and normally are permanently fixed in position. It will be noted, 20 however, that the sleeves 22 may be readily replaced if found necessary in practice.

The sleeves 22 are formed with internal threads and jointly engage the stud bolt 24, 25 which latter forms the connecting medium for securing the butt section 1 and the shaft section 2 together. The stud bolt 24, as illustrated, is preferably formed with respective one-half portions thereof provided 30 with right and left-hand screw threads, but it is obvious that a stud bolt having but one continuous kind of screw threads may be also successfully employed. However, with this latter construction it could not be determined in which section the stud bolt would remain when said sections are separated, while in the former construction this could be determined by holding one section and turning the other, or vice versa, as desired.

The chamber 4 formed in the body member 3, is of sufficient size to house the entire shaft section 2 of the cue, thereby providing compactness to facilitate handling, packing or transportation. The hollow shaft section 2 provides for the reduction in weight of the cue and its economic manufacture by the saving of material.

The modified form of the device illustrated in Figure 2 of the drawing is identical in construction as that above described relatively to the preferred form with the exception that the butt section 25 and shaft section 26 of the former are constructed 55 without an additional outer casing and are formed to provide for the engagement of the buffer casing 9 and ferrules 12 and 21 at respective parts thereof.

What we claim is:—

60 1. A billiard cue comprising a hollow butt member having an open lower end and further permanently closed at a point removed from its upper end, a hollow shaft member permanently closed at a point removed from its lower end, means for detachably connect-

ing the upper end of the butt member to the lower end of the shaft member, a rigid apertured buffer arresting disk mounted against the lower open end of the butt member, a resilient buffer positioned against said disk and means for coupling the buffer with the butt section. 70

2. A billiard cue comprising a butt including a hollow metallic tapered body permanently closed at a point removed from its upper end and having an open lower end, said member further including a fibrous enclosing casing for and terminating at a point removed from each end of said body, a shaft member formed of a hollow metallic tapered body permanently closed at a point removed from its lower end, said shaft member further including a fibrous enclosing casing for its metallic body and terminating at a point removed from the lower end of the latter, ferrules mounted on the opposed ends of said members and abutting against said casings, and means mounted in the closed terminal portions at the opposed ends of said bodies for connecting said members together in abutting relation. 75 80 85

3. A billiard cue comprising a butt including a hollow metallic tapered body permanently closed at a point removed from its upper end and having an open lower end, said member further including fibrous enclosing casing for and terminating at a point removed from each end of said body, a shaft member formed of a hollow metallic tapered body permanently closed at a point removed from its lower end, said shaft member further including a fibrous enclosing casing for its metallic body and terminating at a point removed from the lower end of the latter, ferrules mounted on the opposed ends of said members and abutting against said casings, and means mounted in the closed terminal portions at the opposed ends of said bodies for connecting said members together in abutting relation, an apertured buffer arresting disk positioned against the open lower end of body of the butt member, a resilient buffer mounted against the outer face of the disk, and means engaging with the body of the butt member for coupling said buffer therewith. 100 105 110 115

4. A billiard cue comprising a pair of opposed spaced tapered fibrous casings, a hollow tapered metallic body mounted in each casing and projecting from the inner end thereof, the projecting ends of said bodies being permanently closed, and means for detachably connecting the inner ends of said bodies together. 120 125

5. A billiard cue comprising a pair of opposed spaced tapered fibrous casings, a hollow tapered metallic body mounted in each casing and projecting from the inner end thereof, the projecting ends of said 130

bodies being permanently closed, means for detachably connecting the inner ends of said bodies together, and ferrules mounted on the projecting ends of said bodies and 5 interposed between the inner ends of said casings.

6. A billiard cue comprising a detachable butt member formed of a hollow metallic body enclosed by a snugly fitting casing of 10 fibrous material terminating at a point removed from the lower end of said body whereby the latter will project beyond the lower end of the casing, said body having

an open lower end and its lower terminal portion peripherally threaded, a rigid apertured buffer arresting disk positioned against the lower edge of said body, a resilient buffer mounted against said disk, and means having threaded engagement with the threaded terminal portion of said body 20 and partially overlapping the buffer for coupling it with said member.

In testimony whereof we affix our signatures.

CHARLES E. SEEMAN.
LOUIS V. BARACH.
